UNITED STATES PATENT OFFICE

GEORG HVISTENDAHL, OF TONSBERG, NORWAY

DIVIDING CARD FOR CIGARETTE BOXES

Application filed February 24, 1932, Serial No. 594,899, and in Norway March 2, 1931.

In the usual cardboard packings for cigarettes, in which the cigarettes are placed in several layers, it is customary to place dividing cards between the separate layers, and 5 these cards are often made in the form of pictures or the like for collectors.

The present invention has for its object a dividing card of this type, and the new 10 feature of the invention consists therein that the card is manufactured of a flexible heat resistant and fireproof material such as thin rolled metal, and is adapted to be bent up along the edges in order to form a tray, suitable as an ash tray.

15 The dividing card may be made in the form of a thin aluminum disc, provided with folding lines at a certain distance from the edges in order to facilitate the forming of a tray. Further the part of the dividing card which is to form the bottom of the ash 20 tray may be provided with embossed letters or designs serving the purpose of decoration as well as to lessen the transmission of heat through the ash tray to the supporting table or the like. For the same purpose the lines along which the metal is weakened in order 25 to facilitate bending may be slightly curved in order to give the bottom of the tray a slightly convex shape, whereby it is obtained that the tray will only touch the supporting table with its four corners.

30 Figure 1 is a perspective view of a dividing card,

35 Figure 2 is a perspective view of the tray formed from the card shown in Figure 1,

Figure 3 is a partial plan view of a modification, and

40 Figure 4 is a perspective view of the tray formed from a card having a corner construction as shown in Figure 3.

45 Some forms of the invention are illustrated on the drawing. Fig. 1 is a perspective view of a dividing card 1 of the usual rectangular form and provided with bending lines 2 at a suitable distance from the edges. Further the disc or card is provided with 50 incisions 3, so that the card may easily be altered into a shallow rectangular tray as illustrated on Fig. 2.

Instead of providing the card or disc with

incisions it may be provided with weakened lines 4 at each corner in order that the card or disc may be given the form of a tray with sloping edges 5 as illustrated on Fig. 4.

Also the metal disc forming the dividing card may be provided only with curved 55 weakened lines at a suitable distance from the edges, in which case the ash tray is formed by pinching the four corners, thereby forming a shallow ash tray with a convex 60 bottom.

I claim:

1. A dividing card for cigarette boxes comprising a disc of flexible, fireproof material provided with suitable weakened lines 65 at a certain distance from the edges in order that the card or disc may easily be formed into a shallow ash tray by bending the material along the weakened lines.

2. A dividing card for cigarette boxes as 70 claimed in claim 1, characterized by that the weakened lines are being curved in order to produce a shallow ash tray with convex bottom.

In testimony whereof I have signed my 75 name to this specification.

GEORG HVISTENDAHL.
